SHIPPING DRUM UNLOADER

Samuel S. Roberts, Pittsburgh, Pa.

Application July 18, 1939, Serial No. 285,176

2 Claims. (Cl. 221—79)

This invention is a machine for unloading shipping drums containing plastic substances, such as lubricating greases, one of the objects being to effect such unloading by the application of pressure to the substance in the drum, whereby to obviate the need for the conventional practices of heating the substance to render it fluid, which is sometimes harmful to the substance, or of sucking the substance from the drum, which generally fails to effect complete unloading.

A specific example of the machine embodying the principles of the invention is illustrated by the accompanying drawings, in which:

Figure 1 is an elevation;

Figure 2 is a vertical section;

Figures 3 and 4 are cross sections taken from the lines III—III and IV—IV, respectively, in Figure 1;

Figure 5 is a vertical section at right angles to the section of Figure 2; and,

Figure 6 is a schematic wiring diagram.

More specifically, the machine includes a base 1 having a central portion 2 formed by a circular recess 3 made in a part of the base 1 and which accommodates the depending flange of an upright shipping drum 4. These drums are conventionally made with a recessed bottom with their body or cylindrical portion extending therebeyond to provide the aforementioned flange. This recess 3 performs the double duty of positively positioning the drum and of permitting the portion 2 to directly engage and support the drum bottom.

Three columns 5 rise from the base 1 outside of the portion 2 to a height somewhat greater than twice the height of the shipping drum 4, these columns being spaced 120 degrees apart and their tops supporting a superstructure 6 from which depends a rod assembly in the form of a rotative sleeve 7, journaled in the superstructure, and a screw 8, the screw engaging a nut 9 fixed inside the sleeve 7 and its bottom being bolted to a piston assembly.

This piston assembly comprises a part 10 to which the bottom of the screw is directly bolted and which connects with the piston proper 11 by way of tie bolts 12, the part 10 and piston proper 11 being urged apart by compression springs 13. The piston proper 11 is longer than the drum 4 and has an outside diameter closely approaching the inside diameter of the drum, the top of the piston proper connecting with a spider 14 slidably journaled on the sleeve 7 and the upper portions of the columns 5, this keeping

the piston in alignment with the drum during reciprocation of the piston.

The columns 5 mount an annular cam 15 having a plurality of inclined surfaces 15a supporting a stuffing box assembly 16 by way of rollers 17 working on the surfaces 15a and fixed to the assembly 16. These rollers have handles 17a by means of which the stuffing box assembly can be rotated, the rollers 17 riding up and down the surfaces 15a and vertically reciprocating the stuffing box assembly.

It is to be understood that the drum 4 is a conventional type used for carrying lubricant or other plastics, and having a top ferrule, the drum 15 top being removed when it is placed in the machine so that the piston assembly can enter its interior. The stuffing box assembly 16 includes an inwardly extending flange 18 beneath which is a rubber gasket 19 which fits against the top of 20 the drum flange 4a, the assembly 16 including clips 20 which fit against the bottom of the drum flange 4a and these clips being of the cam type 25 operable by handles 21, operation of these clips serving to compress the gasket 19 against the top 30 of the drum flange 4a to form a grease-tight joint. The stuffing box assembly includes a packing 22 which works against the side of the piston proper 11, this completing the prevention of the leakage of grease past the side of the piston proper.

When the sleeve 7 is rotated, the screw 8 effects reciprocation of the piston assembly fixed to its bottom end, and when this motion is downwardly toward the bottom of the drum, pressure 35 is applied to the contents inside of the drum, the springs 13 compressing during this action. Strain of the springs 13 is prevented by stops 10a and 11a positioned between the relatively moving parts of the piston assembly, these stops 40 contacting to prevent undue compression of the springs 13.

Two of the bolts 12 have tubular bodies 12a, their bottoms being open to the bottom of the piston proper 11 and hence to the contents of 45 the drum, and their tops connecting with pipes 23 which extend upwardly to a position slightly below the spider 14 where they are joined to a horizontally extending pipe 24 to which a flexible 50 hose 25 is attached, this hose having a nozzle 26. It follows that downward movement of the piston assembly applies pressure to the contents 55 of the drum and that these contents are extruded through the nozzle 26. The pipe 24 may, of course, lead directly to the point where the substance extruded from the drum is to be used,

such as, for instance, to the pumps of a lubricating system when the substance is a lubricant.

Rotation of the sleeve 7 is effected by a motor 27 driving through a transmission gear set 28 and a worm drive 29, the worm-wheel of the latter being fixed to the rotative sleeve 7. The transmission gear set 28 has a gear shifting lever 28^a, the motor 27 turning in the same direction at all times and the gears of the transmission gear set 28 being shifted to effect reversal of the sleeve 7. The gears are so arranged as to turn the sleeve 7 slowly in the direction effecting downward movement of the screw 8 and more rapidly when rotated in the opposite direction.

The motor 27 is energized by power lines 30 in which limit switches 31 and 32 are interposed, these limit switches being placed at the top and bottom of one of the columns 5 and being operable by a contactor 33 fixed to the spider 14 which raises and lowers with the piston assembly. These limit switches function to stop the motor 27 when the piston assembly is moved to either of its reciprocatory limits.

A Bourdon tube operated unit 34 is connected by a pipe 35 to the pipe 24, this pipe 35 working through a diaphragm 36 to prevent the entrance of the substance in the drum to the Bourdon tube. This unit 34 contains a switch operated by the Bourdon tube, and this switch is interposed in one of the lines 30 whereby to make the operation of the motor 27 automatically responsive to the pressure exerted on the material in the drum 4 by the piston assembly. Push buttons 31^a and 32^a serve to energize the motor 27 when either of the limit switches is opened by operation of the contactor 33, these switches being depressed during the time necessary for the motor 27 to drive the piston assembly to a position where the contactor 33 leaves the switch it is operating.

Assuming a shipping drum has been placed in the machine and the piston assembly is at its top position, the gear shift lever 28^a is thrown to proper position and the button 31^a is depressed. Since there is no pressure transmitted through the pipe 24 at this time, the Bourdon tube operated switch unit 34 will provide a closed circuit and the motor 27 will start. As soon as the piston assembly is moved downwardly to a point where the contactor 33 ceases to operate the limit switch 31, the push button 31^a may be released. The motor then continues to operate, the piston assembly entering the drum and exerting pressure on its contents, this compressing the springs 13 of the piston assembly.

The Bourdon tube of the unit 34 is adjusted so as to break the circuit to the motor just prior to the time the stops 11^a and 10^a of the piston assembly would contact. The motor is now de-energized until some of the content of the drum is withdrawn by way of the pipe 24, the springs

13 expanding and maintaining a steady pressure on the content of the drum. As these springs 13 expand, the pressure in the drum drops, the Bourdon tube operated switch of the unit 34 operating in due course and the motor again driving the piston assembly downwardly until the unit 34 deenergizes. This continues until all of the content of the drum is driven out. At this time the gear shifting lever 28^a is operated to effect a reversing drive at the higher speed of the sleeve 7, the push button switch 32^a is depressed a sufficient time interval and the piston assembly rises to its uppermost position. The piston assembly contains a vacuum-breaking device in the form of a check valve 37 which permits the entrance of air between the piston proper and the drum bottom as the piston assembly is withdrawn.

I claim:

1. A machine for unloading a shipping drum containing a plastic substance, including a base having a portion for supporting the bottom of the drum when the latter is placed upright thereon, columns rising from said base outside of said portion, a superstructure supported by the tops of said columns, a rod depending from said superstructure, a piston fitting the drum and mounted by said rod so as to work in the drum when the latter is positioned upright with its bottom on said base portion, and powered means for causing said rod to force said piston downwardly, said columns mounting an annular cam supporting a stuffing box for the top of the drum, said piston being longer than the drum is deep and its side working in said stuffing box, the latter being associated with said cam so that relative rotation therebetween effects vertical movement of said stuffing box for engagement and release of the latter respecting the drum top.

2. A machine for unloading a shipping drum containing a plastic substance, including a base having a portion for supporting the bottom of the drum when the latter is placed upright thereon, columns rising from said base outside of said portion, a superstructure supported by the tops of said columns, a rod depending from said superstructure, a piston fitting the drum and mounted by said rod so as to work in the drum when the latter is positioned upright with its bottom on said base portion, and powered means for causing said rod to force said piston downwardly, said columns mounting a stuffing box for the top of the drum, said piston being longer than the drum is deep and its side working in said stuffing box, the latter being mounted by said columns by means effecting vertical movement of said stuffing box for engagement and release of the latter respecting the drum top.
